PISTON EXPANDER

William H. Wheeler, Denver, Colo., assignor to
Francis J. Casey, Denver, Colo.

Application March 29, 1937, Serial No. 133,624

8 Claims. (Cl. 80—5)

This invention relates to method of expanding hollow or skirted pistons and especially to expanding pistons of the type common to internal combustion motors as used in automobiles and the like and to a device for accomplishing such expansion in accordance with such method.

An object of the invention is to provide a method and device for expanding pistons in accordance with which and by means of which pressure is exerted coincidently upon the outer and inner surfaces of the piston wall at any desired point and in degree sufficient to compress, and thereby lessen the thickness of the wall at such point, resulting in a corresponding expansion of the periphery of the piston at such point.

A further object is to provide a method and apparatus for applying pressure, rollingly and coincidently to the outer and inner surfaces of the piston wall at any desired point thereof.

A further object is to provide a device of the class described which is, in size, a small tool, operable by hand to full efficiency, and in which there is combined, with the above features, simplicity of construction and operation, strength, durability and great economy as to both construction and operation.

With these and other objects in view, as will more fully hereinafter appear, my invention comprises certain novel steps, operations, constructions, combinations and arrangements of parts as will now be described and claimed and as illustrated in the accompanying drawing, in which there is illustrated a preferred embodiment of my invention of an apparatus for practicing my said method and in which drawing

Figure 1 is a side elevation of my expander.

Figure 2 is a vertical, longitudinal section of the expander taken centrally thereof, as upon line 2—2 of Figure 3, but showing certain parts in full lines.

Figure 3 is a fragmentary section on line 3—3 of Fig. 1.

In course of use, pistons and the cylinders in which they operate lose their normal exact sliding interrelation. Through wear or other causes the inner cylinder wall or the outer piston wall or both become distorted from the normal, resulting in looseness "piston slap" and other undesired results.

The expansion of the outer wall of the piston at the proper point or points will reestablish substantially the normal exact sliding interrelation of piston and cylinder.

Various methods and devices for accomplishing such expansion and for limiting the same to

the desired degree and extent in area have been used but have been found subject to some or all of the objections of expense, bulk, clumsiness, lack of exact control, difficulty in operation and general inefficiency.

I have found that from compression of the piston wall, expansion of the periphery results. Excessive compression at any one point would, however, result in bulging the wall adjacent such point of compression instead of evenly expanding the desired area.

It is necessary, therefore, to have exact control of the degree of pressure exerted and, likewise, to move the point of application of pressure throughout the area to be expanded while retaining such control. I have found that by the application of pressure on inner and outer surfaces of the piston wall at opposed points and applying such pressure rollingly, the piston wall may be compressed to the desired degree, throughout the desired area resulting in the expansion of the outer surface of the piston wall within such area and to the degree necessary to take up the looseness and substantially reestablish the exact sliding fit between the piston and the cylinder.

As a means of operating in accordance with my said method, I have provided the device illustrated in the drawing comprising a suitable base 1, adapted to be fastened to a table or, preferably, gripped in an ordinary vise. On one end the base carries a split support 2 between the upper ends of which is pivotally mounted, as by pivot screws 3, a barrel 4 carrying a shaft 5 centrally, longitudinally and rotatably therein. At its forward end the shaft 5 carries a knurled wheel 6 which may be formed integral with shaft 5. At its rear end shaft 5 is provided with a handle 7 securely affixed thereto by any suitable means. A tapered fit indicated at 8, secured by nut 9 has been found sufficient.

Approximately midway of the barrel I provide a yoke 10, carried by base 1 and enclosing barrel 4, the sides of the yoke being spaced to permit vertical movement of the barrel 4 therebetween. Within the yoke 10 beneath barrel 4 I provide coiled spring 11 for normally forcing barrel 4 upwardly and in the top of the yoke I provide a threaded shaft 12 having handle 13 for forcing the barrel downwardly against the pressure of spring 11.

Beneath knurled wheel 6 I provide a roller 14 rotatably mounted by means of trunnions 15 in notched standards 16. On both sides of roller 14 the base is raised as at 17 whereby to provide,

between the standards 16 and the sides 17, a well 18 for oil whereby to keep the surface of roller 14 oiled as it rotates.

The base 1, split support 2, yoke 10, standards 16 and oil well sides 17 may be and preferably are a single casting.

The barrel 4 is reduced as at 19 and 20 to avoid interference with wrist pin bosses or other projections within the piston.

In operation the open end of the piston to be operated upon is projected over knurled wheel 6 and barrel 4 to the extent necessary to bring beneath wheel 6 that part of the piston wall to be compressed, which part will then be between wheel 6 and roller 14. Barrel 4 is then forced down by operating handle 13 until wheel 6 is exerting the desired pressure at the proper point on the inner surface of the piston wall, roller 14 exerting a corresponding pressure on the opposed point on the outer surface. Handle 7 is then swung back and forth to the extent necessary to cause the piston wall to be rolled between wheel 6 and roller 14 to the extent of the width of the area to be expanded. The exertion of this rolling pressure will compress and lessen the thickness of the wall of the piston, throughout the area thus rolled, and the periphery of the piston will be correspondingly expanded throughout that area. The operation may be repeated at successive points lengthwise of the piston as may be required.

The downward pressure of wheel 6 on the piston wall may be increased from time to time as desired by operation of handle 13.

Barrel 4 functions as an elongated supporting bearing for shaft 5. In this connection it will be understood that a very considerable pressure is exerted through wheel 6. This puts a heavy strain on shaft 5 requiring substantial supporting bearing therefor while providing for insertion of wheel 6 into the interior of the piston without interference. Barrel 4 is a convenient and efficient structure for such purpose.

In actual, everyday commercial operation the method and apparatus hereinabove described have proven to be of very great efficiency, convenience and general utility for the intended purpose.

While I have illustrated and described in detail the preferred embodiment of my expander I do not wish to be confined to such details as there will occur to those skilled in the art many ways in which the details of construction may be varied without departing from the spirit and scope of my invention as above described and as defined in the appended claims.

I claim:

1. An expander for hollow pistons comprising, in combination, a base carrying a freely rotatable smooth roller, a shaft carrying a knurled wheel and rotatable within a sleeve, which sleeve is pivoted to the base at a distance from said smooth roller greater than the depth of the piston, whereby to permit the wheel to be swung toward or away from the roller, means for rotating the shaft and means for exerting pressure on the sleeve whereby to grip a cylinder wall between the roller and wheel when the wheel is inserted into a piston.

2. An expander for hollow pistons comprising, in combination, a base carrying an oil reservoir and a smooth roller freely rotatable on the base and partially within the reservoir, a shaft carrying a knurled wheel and rotatable within a

sleeve, which sleeve is pivoted to the base at a distance from said smooth roller greater than the depth of the piston, whereby to permit the wheel to be swung toward or away from the roller, means for rotating the shaft and means for exerting pressure on the sleeve whereby to grip a cylinder wall between the roller and wheel when the wheel is inserted into a piston.

3. An expander for hollow pistons comprising, in combination, a base carrying a smooth roller freely rotatable but otherwise rigid, a shaft carrying a knurled wheel and rotatable within a sleeve, which sleeve is pivoted to the base at a distance from said smooth roller greater than the depth of the piston, whereby to permit the wheel to be swung toward or away from the roller, means for rotating the shaft and means for exerting pressure on the sleeve whereby to grip a cylinder wall between the roller and wheel when the wheel is inserted into a piston, said sleeve extending along said shaft approximately to said wheel.

4. In a piston expander having a base with a sleeve pivoted thereto near one end, said sleeve enclosing a shaft with a short knurled roller at the end thereof farthest from the pivot and means at the end near the pivot for rotating the shaft with its knurled roller, a long, smooth roller mounted in said base beneath said knurled roller for free rotation responsive to rolling contact with its periphery.

5. In a piston expander having a base with a sleeve pivoted thereto near one end, said sleeve enclosing a shaft with a short knurled roller at the end thereof farthest from the pivot and means at the end near the pivot for rotating the shaft with its knurled roller, a long, smooth roller mounted in said base beneath said knurled roller for free rotation but otherwise rigid.

6. In a piston expander having a base with a sleeve pivoted thereto near one end, said sleeve enclosing a shaft with a short knurled roller at the end thereof farthest from the pivot and means at the end near the pivot for rotating the shaft with its knurled roller, a long, smooth roller mounted in said base beneath said knurled roller for free rotation responsive to rolling contact with its periphery, said long roller being mounted with its lower portion in an oil reservoir carried by said base whereby the surface of said roller will, upon rotation, move through and be coated with oil.

7. In a piston expander having a base with a sleeve pivoted thereto near one end, said sleeve enclosing a shaft with a short knurled roller at the end thereof farthest from the pivot and means at the end near the pivot for rotating the shaft with its knurled roller, a trunnion carriage formed on the base beneath the knurled roller and a long smooth trunnioned roller freely rotatable in said carriage.

8. In a piston expander having a base with a sleeve pivoted thereto near one end, said sleeve enclosing a shaft with a short knurled roller at the end thereof farthest from the pivot and means at the end near the pivot for rotating the shaft with its knurled roller, a trunnion carriage formed on the base beneath the knurled roller and a long smooth trunnioned roller freely rotatable in said carriage and an oil reservoir carried by the base beneath said smooth roller and enclosing the lower portion thereof.

WILLIAM H. WHEELER.
